UNITED STATES PATENT OFFICE.

JAMES H. VAN DORN AND JOHN T. WHITEHOUSE, OF CLEVELAND, OHIO, ASSIGNEES TO THE VAN DORN IRON WORKS COMPANY, OF CLEVELAND, OHIO, A CORPORATION OF OHIO.

LOCK MECHANISM FOR CELL-DOORS.

1,222,821.

Specification of Letters Patent.

Patented Apr. 17, 1917.

Application filed August 18, 1913. Serial No. 785,273.

To all whom it may concern:

Be it known that we, JAMES H. VAN DORN and JOHN T. WHITEHOUSE, citizens of the United States, and residents, respectively, 5 of Cleveland, in the county of Cuyahoga and State of Ohio, have invented a certain new and useful Improvement in Lock Mechanism for Cell-Doors, of which the following is a full, clear, and exact description.

The object of this invention is to provide a strong, simply constructed lock which will automatically lock a cell door when the door is closed, and mechanism by which said lock 15 can be unlocked from a distant station; also a lock and operating mechanism therefor which the prisoners cannot tamper with and render useless. The invention consists in the construction and combination of parts here- 20 inafter described and pointed out in the claims and shown in the drawing, in which

Figure 1 is a front elevation of cell construction in which the present invention is embodied. Fig. 2 is a sectional plan of the 25 front of said cells. Fig. 3 is a front view of the lock when the front plate of the lock case is removed. Fig. 4 is a sectional plan view showing parts within the lock case in the position they occupy when a cell door is 30 locked. Fig. 5 is a similar plan view showing the position the parts occupy when the cell door is unlocked. Fig. 6 is a sectional view from the bottom of the lock case. Fig. 7 is a sectional side view through the box 35 casing above the cell doors showing the lock operating mechanism therein contained. Fig. 8 is a plan view of the lock operating and controlling mechanism showing the position it occupies when the cell door is opened. Fig. 9 is a similar view showing a part of the cell door and the lock controlling mechanism in the positions they occupy when the cell door is closed.

Referring to the parts by letters, A represents the lock case which is to be secured to the door jamb C, in such position that a notched bolt G carried by the cell door F will pass through a hole a^1 in the edge of the lock case, to a position to be engaged by the 50 latch B in said case.

This latch B is pivoted on a vertical pivot H, and it is provided with two lugs b which are adapted to enter notches g , g^1 , in the upper and lower edges of the bolt G. Within the latch case are springs b^1 which act to

swing the latch forward,—that is to say, in the locking direction.

In the lock case also is a bolt-hole guard D. This guard is in the form of an open frame which is pivoted on the same pivot 60 H as that on which the latch is pivoted, and it is under the influence of springs d tending to swing it forward into the position shown in Fig. 5 where it lies entirely across the hole a , and thereby prevents the introduc- 65 tion into the lock case of paper or any other foreign matter. The latch lies and operates within the open center of the bolt-hole guard.

Two rock shafts J and K are mounted in 70 the lock case in front of the two swinging members B and D referred to, and these shafts extend upward out of the lock case through a hollow vertical member T into the box casing T^1 which is above the door openings of the cell structure. The shaft J has fixed to it within the lock casing a cam arm j which is adapted to engage the front face of the latch member and thereby swing it rearward into the bolt releasing position. 80 The other rock shaft K has a cam arm k fixed to it for engagement with the front edge of one of the side members of the guard frame D, whereby when the rock shaft is turned, this frame will be swung rearward 85 to a position to uncover the hole a in the case and thereby permit the entry of the bolt into the same. The same member which carries the cam arm k carries also a hook k^1 . Likewise the side member of the bolt-hole guard 90 frame D has a hook d^1 with which the hook k^1 is adapted to interlock.

On the upper ends of the two shafts J and K are arms by which they may be operated and controlled. The arm k^2 is fixed to the 95 shaft K, and lies in the path of a rod f fixed to the cell door F. Likewise there is a spring k^3 acting upon arm k^2 and tending to turn the rock shaft K in that direction which will permit the bolt guard to swing 100 forward over the bolt hole.

Fixed to the shaft J are two arms j^2 and j^3 . The arm j^3 is connected with a rod R, located in the box casing T^1 before mentioned. This rod is connected with a cable 105 m which extends over suitable guide sheaves down into the lock box S in the jailer's corridor at the end of the row of cells, and there this cable is connected with an operating lever M. The other arm j^2 is provided 110

with a shoulder j^4 so placed that a pivoted spring actuated trigger N may engage therewith.

If, for example, the door is closed and 5 locked, the parts within the lock case will be in the position shown in Fig. 3. If, now, the attendant in the jailer's corridor actuates the lever M in the lock box referred to he will, through the described cable m, rod 10 R and arm j^3 turn rock-shaft J in a direction such as will swing the latch B rearward and thereby release the bolt G. At the same time the arm j^2 will be so turned that the trigger N will fly behind the shoulder j^4 and 15 thereby the rock-shaft J will be held in the described position, namely, the position in which the latch has released the bolt. When the door is opened and the bolt G withdrawn from the lock case, the guard frame 20 D which had before been held back by engagement with said bolt will swing forward and so cover the bolt hole a. The arm k^2 attached to the rock shaft in the box casing T will occupy the position relative to 25 the adjacent parts likewise as shown in Fig. 9. Also the shaft K will be so turned by the operating spring k^3 as to cause the engagement of the two hooks d^1 and k^1 , whereby the bolt hole guard is locked in the closed 30 position.

When, now, the door is closed, the bar f will engage with arm k^2 and will rock the rock shaft and so withdraw the guard plate from its position over the bolt opening; and 35 thereby the bolt will be permitted to enter the lock case. When the bolt is in the lock case and just as the door is fully closed this same bar f will strike the trigger N and will withdraw it from engagement with 40 shoulders j^4 , and thereby spring j^5 acting on arm j^2 will rock rock-shaft J so as to release the latch B from restraint, and thereupon the spring b^1 will move the said latch so that its lug b will enter the notches in the 45 bolt.

It is apparent from the foregoing that when by the opening of a cell door its bolt G has been withdrawn from the lock case, the bolt hole guard will immediately and 50 automatically be swung over the bolt hole, and so locked that the prisoner operating on the bolt hole guard cannot move it away from its position over said bolt hole. A prisoner therefore cannot stuff paper or 55 other refuse in the lock case and so render it useless.

Where there is a row of cells, each provided with the above described mechanism, there will be a plurality of rods R, and 60 cables m. These are all in the box casing T¹ and near the rear wall thereof. The hanger plate F¹ of each cell door passes up into the box casing through a slot t^1 in the bottom thereof. Prisoners frequently employ great ingenuity in rendering the cell 65

door locking mechanism inoperative. In order that they may not push a rod up through the slot t^1 , and with it break the rods R or cables m, or render them useless, a guard plate W is fixed in the box casing 70 between the slot t^1 and said rods.

Having described our invention, we claim:

1. In door locking mechanism, the combination of a lock case having in one wall a hole for the passage of the bolt, a spring 75 actuated pivoted latch within said lock case, a spring actuated pivoted bolt hole guard located within the lock case, means for moving the latch in the bolt releasing direction, and independent means for moving the bolt 80 hole guard to the open position.

2. In door locking mechanism, the combination of a lock case having in one wall a hole for the passage of the bolt, a spring 85 actuated pivoted latch within said lock case, a spring actuated pivoted bolt hole guard located within the lock case, means for moving the latch in the bolt releasing direction, and independent means for moving the bolt 90 hole guard to the open position, two trains of 95 mechanism extending out of the lock case to distant operating positions, one of said trains of mechanism having an operative connection with the means for moving the bolt hole guard to the open position, and one of said trains of mechanism having an operative connection with the means for moving the latch in the bolt releasing direction.

3. In door locking mechanism, the combination of a lock case having in one wall an opening for the passage of the bolt, with a spring actuated latch, and a bolt-hole 100 guard, both pivoted within the latch case on the same pivot rod, the bolt-hole guard 105 having an open center in which the latch is movable, means for moving the latch in the bolt releasing direction, means for moving the bolt-hole guard to the open position, a spring for moving said guard to the bolt- 110 hole closing position, and means for locking said bolt hole guard in the bolt-hole closing 115 positions.

4. In door locking mechanism, the combination of a lock case having in one wall an opening for the passage of the bolt, with a spring actuated latch pivoted within said 120 case, a spring actuated bolt-hole guard also pivoted within said case, a vertical rock-shaft entering into the case and having 125 therein an arm for engagement with the bolt-hole guard to move it to the open position, and interlocking hooks, one carried by the bolt-hole guard, and one by said rock-shaft, whereby the bolt-hole guard will be 130 locked in the hole closing position.

5. In door locking mechanism, the combination of a lock case having in one wall an opening for the passage of the bolt, with a spring actuated latch and a spring actu- 130

ated bolt-hole guard, both located within said case, two vertical rock shafts entering the case, one carrying an arm for engagement with the latch to open the same, and 5 one carrying an arm for engagement with the bolt-hole guard to open it, an arm fixed to the rock-shaft which is associated with the latch, which arm is provided with a shoulder, a spring actuated trigger adapted 10 to engage said shoulder to hold the latch in the bolt releasing position, an operating arm fixed to the upper end of the other rock shaft, a sliding door carrying a notched bolt adapted to enter the hole in the lock case, 15 and carrying also a rod arranged to engage the arm attached to the shaft which operates the bolt-hole guard and to likewise engage said trigger.

6. In door locking mechanism, the combination of a lock case having in one wall an opening for the passage of the bolt, with 20 a spring actuated latch and a spring actuated bolt-hole guard, both located within said case, two vertical rock shafts entering 25 the case, one carrying an arm for engagement with the latch to open the same, and one carrying an arm for engagement with the bolt-hole guard to open it, an arm fixed to the rock shaft which is associated with 30 the latch, which arm is provided with a shoulder, a spring actuated trigger adapted to engage said shoulder to hold the latch in the bolt releasing position, an operating arm fixed to the upper end of the other rock 35 shaft, a sliding door carrying a notched bolt adapted to enter the hole in the lock case, and carrying also a rod arranged to engage the arm attached to the shaft which operates the bolt-hole guard and to likewise engage 40 said trigger, and springs operating on said two rock-shafts to turn them in the direc-

tion to move the bolt-hole guard in the hole closing direction and to move said latch to the bolt engaging position.

7. In door locking mechanism, the combination of a lock case having in one wall an opening for the passage of the bolt, with 45 a spring actuated latch and a spring actuated bolt-hole guard, both located within said case, two vertical rock-shafts entering 50 the case, one carrying an arm for engagement with the latch to open the same, and one carrying an arm for engagement with the bolt-hole guard to open it, an arm fixed to the rock shaft which is associated with 55 the latch, which arm is provided with a shoulder, a spring actuated trigger adapted to engage said shoulder to hold the latch in the bolt releasing position, an operating 60 arm fixed to the upper end of the other rock shaft, a sliding door carrying a notched bolt adapted to enter the hole in the lock case, and carrying also a rod arranged to engage the arm attached to the shaft which operates the bolt-hole guard and to likewise engage 65 said trigger, and springs operating on said two rock shafts to turn them in the direction to move said latch to the bolt engaging position, and interlocking hooks 70 within the lock case carried by the bolt-hole guard, and the associated shaft for locking the bolt-hole guard in the hole closing position.

In testimony whereof, we hereunto affix our signatures in the presence of two witnesses.
